UNITED STATES PATENT OFFICE.

GRACE HUNTINGTON BUCKLAND, OF FREMONT, OHIO.

DESIGN FOR A FABRIC.

SPECIFICATION forming part of Design No. 35,278, dated November 5, 1901.

Application filed March 28, 1901. Serial No. 53,362. Term of patent 14 years.

To all whom it may concern:

Be it known that I, GRACE HUNTINGTON BUCKLAND, a citizen of the United States, and a resident of the city of Fremont, in the county 5 of Sandusky and State of Ohio, have invented and produced a new and original Design for Fabrics, of which the following is a specification, reference being had to the accompanying drawing, forming part hereof.

10 This design relates to the ornamentation of cotton, silk, woolen, paper, celluloid, and other fabrics.

In the accompanying drawing, making a part of this specification, I have shown a plan 15 view of my design.

As shown in the drawing, the outside of the design is national in character, namely: At each corner is a shield containing an eagle with outspread wings and carrying in his 20 mouth a scroll. A shield is present in front

of his breast, and held by the claws of one foot is a branch and in the grasp of the other a series of arrows. Above the eagle is a wreath inclosing stars. Between the adjacent corners of the shields is a series of stars having 25 in general the conformation of a loop, the stars increasing in size toward the bottom of the loop.

Having described my invention, what I claim as new and of my invention, and desire 30 to secure by Letters Patent, is—

The design for a fabric herein shown and described.

In testimony whereof I have signed my name to this specification in the presence of 35 two subscribing witnesses.

GRACE HUNTINGTON BUCKLAND.

Attest:

B. R. DUDROW,
GEORGE BUCKLAND.
